PRINTING DEVICE

Filed March 1, 1930

UNITED STATES PATENT OFFICE

ELMER F. RICHTER, OF PARK RIDGE, ILLINOIS, ASSIGNOR TO ADDRESSOGRAPH COMPANY, OF WILMINGTON, DELAWARE, A CORPORATION OF DELAWARE

PRINTING DEVICE

Application filed March 1, 1930. Serial No. 432,483.

This invention relates to printing devices which are stored in accordance with a card index system and are adapted to be run through an addressing or other machine for printing, and more particularly to that class of printing devices which comprises a frame having suitable retaining means and a printing plate having type characters embossed thereon and detachably engaged with said retaining means. The type characters appear in relief and in reverse reading order on the front of the plate, and in intaglio in correct reading order on the back of the plate. The plate is inserted in the retaining means on the frame with its front exposed and its back facing the body of the frame. Since the printing characters on the plate are only exposed in reverse reading order they are not easily read and it has been the practice to provide a card which carries an imprint of the type form on the plate, or a part of it, and is detachably engaged with retaining means on the frame above the printing plate where it can be easily read in accordance with a card index system. But it is often desired to provide the printing plate with a printing form consisting of more than an address and this printing form may run to a number of lines in addition to the address, the additional lines being disposed in a manner designed to print on notices, bills, or other articles in a predetermined arrangement. If the card were made of a size to receive a full impression from the printing form on the plate a frame correspondingly larger would be required and this would make a printing device of an unusual size which would not be adapted for the filing cabinets and machines now used in connection with such printing devices. Consequently it has been the practice to provide a card smaller than the printing plate and adapted to receive an impression of only a part of the printing form on the plate. Such a card limits the classification of the device to the information disclosed by the card, whereas it may be important to classify the device according to other information on the plate.

My invention has for its object to enable the use of the printing frame and plate and

card in the usual manner hereinbefore described and also to enable the printing plate to be read on the intaglio side, the type characters being in correct reading order at the back of the device. 55

My invention has the further advantage of enabling a printing device to be stored with the face of the plate and the card in front, or with the back of the plate and the back of the frame in front so that the device may be 60 classified according to the information appearing on the card or according to other information appearing on the plate.

In the accompanying drawing, I have shown the invention in a selected embodiment 65 and, referring thereto,

Fig. 1 is a front view of a printing device, Fig. 2 is a back view of a printing device, Fig. 3 is a front view of the frame of the printing device; and 70

Fig. 4 is a sectional view on the line 4—4 of Fig. 1.

Referring to the drawing, the frame 5 is made of relatively thin sheet metal and it is provided with a top bead 7 and a bottom 75 bead 12. The printing plate 10 is also made of sheet metal and it has a plurality of lines of type characters embossed in relief on the front thereof, Fig. 1. This plate is removably held in place on the frame by retaining means comprising the bead 12, end stops 13, and lips 14 which overhang projections 19 on the top edge of the plate. A wedge projection 20 on the top edge of the plate between the projections 19 is arranged to engage a 80 holding device 22 on the frame with a wedging action to hold the plate in the retaining devices and in substantially fixed position on the frame. The projections and the wedge projection on the plate are so positioned relative to the lips 14 and the holder 22 that when the lower edge of the plate is inserted in the bed 12 the upper edge of the plate will clear the lips and holder so that the back of the plate may flatly engage the front 85 of the frame with the projections 19 between the holder and the lips 14. The plate may then be slid endwise to engage the projections 19 with the lips 14 and the wedge projection 20 with the holder 22, Fig. 1. To 90 95 100

remove the plate from the frame the right or left end of the frame is sprung or bent back slightly until the end of the plate clears the stops 13 whereupon the plate may be 5 moved endwise over the sprung end of the frame until the projections 19 register with the spaces between the holder 22 and the lips 14 after which the upper edge of the plate may be tilted forward slightly and the plate 10 removed by lifting it out of the bead 12. In order that the printing characters may be read at the back or intaglio side of the plate when the plate is mounted in the frame the body of the frame is cut out to provide an 15 opening 21 of sufficient size to disclose therethrough all of the type characters on the plate, or as many lines or parts thereof as may be desired. The frame shown in Fig. 2 has a large opening through which all of the 20 printing characters on the plate are visible at the back of the printing device in intaglio and in correct reading order so that they can be easily read. The marginal edge of the opening should overlap the plate preferably 25 at the top, bottom and sides to form a substantial support for the plate when it is mounted in the frame. The ends of the opening approach closely the spacing flanges 15 which are provided on the back of the frame 30 to space the printing devices one from another in a drawer or in a stack to protect the faces of the printing characters. The opening and the top and bottom beads 7 and 12 are about the same length and the 35 end portions of the frame are readily yieldable with respect to the rest of the frame so that either end of the frame may be easily bent back sufficiently to clear the stops 13 and permit removal of the plate from the frame 40 as heretofore described. The bending of the flanged end portion of the frame to clear the stops from the end of the plate is facilitated by the opening in the frame which permits the ends of one or more fingers to press for- 45 ward on the back of the plate while the thumb is pressing backward on the end of the frame thereby, by combined action, clearing the stops from the end of the plate. While this operation is being performed by 50 the thumb and fingers of one hand the thumb and fingers of the other hand may be pressing on opposite sides of the plate at the other end thereof and sliding the plate endwise to removal position. It is not necessary 55 under any conditions to bend the end of the frame sufficiently to permanently distort it because very little bending is required under any circumstances and when pressure is applied to the plate at the same time that pres- 60 sure is applied to the end of the frame, as described, there is such a small degree of bending of the frame that it is negligible so far as possible damage to the frame is concerned. A card 9 is adapted to be removably 65 engaged with the top bead 7, end stops 13,

70 lips 6 and the holder 22 which form retaining devices and hold the card on the frame. To remove the card the frame is sprung or bent at one end, as previously described, and then the card is moved endwise until it has cleared the retaining devices.

75 The invention makes it possible to use the printing device in the manner which has been customary heretofore with the card disclosing an impression sufficient at least for classification purposes and so that it can be easily read in a storage drawer with the type face of the plate at the front of the device, as shown in Fig. 1. It also enables the printing device to be stored in reverse position 80 with the back of the frame at the front so that the printing characters on the printing plate, in whole or in part, may be read in intaglio but in correct reading order through the opening in the body of the frame. For 85 example, for alphabetical classification, the printing device may be arranged with an index tab as shown in Fig. 1, and for monthly classification the printing device may be arranged with a tab as shown in Fig. 2. These 90 classifications are to be understood only as illustrative examples. The opening 21 not only provides a sight for the intaglio side of the printing plate, but it serves to lighten the frame and the printing device without weakening it for general use. This is especially 95 desirable in large lists where weight is a matter of importance. And the opening also presents the advantage of enabling the operator to continue his hold upon the plate 100 throughout the insertion and removal operation and additionally facilitates these operations.

105 I have shown the invention embodied in a frame with a card, but the card and the provision therefor may be omitted and other changes may be made to adapt the invention for different printing devices and for different uses or otherwise within the scope of the following claim:

110 I claim:

115 In a printing device which has a frame having a plurality of end stops spaced apart and stamped up from the frame in substantially vertical alignment adjacent the ends of the frame, a bead along the lower edge of the frame, retaining lips struck up from the frame and spaced from and disposed opposite said bead, and a holding device intermediate the retaining lips, said frame having an opening therein with the edges thereof spaced inwardly from said end stops, retaining lips, and bead and facilitating springing of the frame, the combination of a printing plate 120 having printing characters embossed in relief on one face thereof and appearing in intaglio on the opposite face, and a wedge projection on one edge of said printing plate and adapted to be engaged with said holding device and said retaining lips when the other 125 130

edges of said plate are engaged with said bead and said end stops, the opening in said frame disclosing the intaglio faces of said type characters to facilitate reading thereof and after 5 fording access to said plate whereby said plate may be grasped on opposite faces thereof to facilitate sliding of the plate along the frame when the frame is sprung to clear the end stops from an edge of the plate whereby 10 the plate may be removed from the frame after limited movement of the plate disengaging the wedge projection thereon from the holding device and retaining lips.
